(57) CLAIM

The ornamental design for a combined tablet with cover, as shown and described.

DESCRIPTION

FIG. 1 is a perspective view of a combined tablet with cover, showing our new design in a closed configuration;

FIG. 2 is a perspective view of the combined tablet with cover in an alternate configuration;

FIG. 3 is another perspective view of the combined tablet with cover in an alternate configuration;

FIG. 4 is a front view of the combined tablet with cover in a closed configuration;

FIG. 5 is a left-side view thereof;

FIG. 6 is a top view thereof;

FIG. 7 is a bottom view thereof;

FIG. 8 is a back view thereof;

FIG. 9 is a right-side view thereof;

FIG. 10 is a bottom view of the combined tablet with cover in an alternate configuration;

FIG. 11 is a left-side view thereof;

FIG. 12 is a bottom view of the combined tablet with cover in an alternate configuration;

FIG. 13 is a left-side view thereof;

FIG. 14 is a top view of the combined tablet with cover in an alternate configuration;

FIG. 15 is a right-side view thereof; and,

FIG. 16 is a back view thereof.

The broken lines in the drawings illustrate portions of the combined tablet with cover that form no part of the claimed design.

1 Claim, 10 Drawing Sheets
